(57) **CLAIM**

The ornamental design for a cover for ink cartridge, as shown and described.

DESCRIPTION

FIG. 1 is a top perspective view of a cover for ink cartridge of the present invention;

FIG. 2 is a bottom perspective view thereof;

FIG. 3 is a front elevational view thereof, the rear view being a mirror image;

FIG. 4 is a left side view thereof, the right side being identical;

FIG. 5 is a top perspective view of a second embodiment of FIG. 1;

FIG. 6 is a bottom perspective view of FIG. 5, the left, right, front and rear views are the same as those in the first embodiment, FIGS. 1-4;

FIG. 7 is a top perspective view of a third embodiment of FIG. 1;

FIG. 8 is a bottom perspective view of FIG. 7, the left, right, front and rear views are the same as those in the first embodiment, FIGS. 1-4;

FIG. 9 is a top perspective view of a forth embodiment of FIG. 1; and,

FIG. 10 is a bottom perspective view of FIG. 9, the left, right, front and rear views are the same as those in the first embodiment, FIGS. 1-4.
